UNITED STATES PATENT OFFICE.

PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

TESTING DEVICE AND METHOD FOR RAILWAY-TRAFFIC-CONTROLLING APPARATUS.

Application filed July 13, 1926. Serial No. 122,119.

My invention relates to devices for testing railway traffic controlling apparatus and to methods of testing such apparatus. My invention is particularly adapted for, though by no means limited to, use in connection with apparatus of the type known as intermittent inductive train control apparatus comprising a train carried core, having two windings thereon, and co-operating with inductors located in the trackway which are arranged to vary the reluctance of the magnetic circuit through said core.

I will describe one form of testing device embodying my invention and a method of testing with such device, and will then point out the novel features thereof in claims.

In the accompanying drawing, the single figure is a view, partly diagrammatic, of one form of testing device embodying my invention applied to the train carried core of one form of railway traffic controlling apparatus.

Referring to the drawing, the reference character A designates a magnetizable train carried core having two spaced pole pieces 1 and 2. This core A is provided with two windings 3 and 4. The reference character R designates a train carried relay which is at times supplied with current from a suitable source of energy such as a battery 5 over its own front contact 6 in series with the winding 4 and a variable resistance 7. The reference character V designates a magnet valve which is arranged to apply the brakes on the train when the magnet is de-energized. Valve V is provided with a circuit including a battery 9, a front contact 8 of relay R, winding 3, and an adjustable resistance 10.

The apparatus thus far described is suitable for use in a train control system in which trackway inductors are located at intervals along the trackway. Each of these trackway inductors comprises a core of magnetizable material, and the parts are so disposed that as the train passes each inductor the pole pieces 1 and 2 are bridged by the core of the inductor thereby materially reducing the reluctance of the magnetic circuit through the core A. Means may also be provided for nullifying the effect of the trackway inductor upon the train carried core. For example the inductor core may

be provided with a nullifying winding the terminals of which may be at times connected together. Under these conditions, that is, when the circuit is closed for the winding on the trackway inductor, the effective reluctance of the inductor core is comparatively high to a changing flux, and the inductor will cause substantially no change in the reluctance of the magnetic circuit through core A on a train passing at any ordinary speed.

As shown in the drawing, relay R is energized, so that current is flowing from battery 5, through winding 4, and current is also flowing from battery 9, through winding 3 and valve V, thereby preventing the brakes from being applied. The current through winding 4 causes a small magnetic flux in core A, and the current through winding 3 causes a large flux through the core. The parts are so arranged that the fluxes caused by currents in these two windings add. When the core A is not over a trackway inductor the reluctance of the magnetic circuit through core A is comparatively high, the resistances 7 and 10 are so adjusted that under these conditions relay R and valve V are energized. When the train passes a trackway inductor which has its nullifying winding open-circuited the reluctance of the magnetic circuit through core A is materially decreased. The flux due to the current in winding 3 is therefore considerably increased, and as a result of this increased flux an electromotive force is induced in winding 4. This induced electromotive force causes a current to flow through relay R which current is in opposition to the current supplied by battery 5 tending to prevent the increase of flux through A according to Lenz' law, and is of sufficient magnitude to cause relay R to become de-energized. Contact 8 of relay R is therefore opened and magnet valve V becomes de-energized to cause an automatic application of the brakes. The engineman can prevent this automatic application of the brakes as the train a trackway inductor by closing circuit controller K. This circuit controller is shunted around contact 6 of relay R. If the engineman operates circuit controller K as the train passes an inductor the relay R may be de-energized as before, but as soon as the train passes the

inductor, current will again flow through the relay from battery 5, and the relay will again become energized to re-close the circuit for valve V and prevent an automatic application of the brakes. Of course, if the circuit for the nullifying winding of the trackway inductor is closed the inductor will have too small an effect to operate relay R of the train carried apparatus.

In railway traffic controlling apparatus of the type just described it is sometimes desirable to test the train carried apparatus without actually moving the locomotive at a definite speed past a trackway inductor, and to do this, I provide a bar B of magnetizable material which is fastened across the pole pieces 1 and 2 of the core A by suitable means such as clamps 13. The ends of bar B are separated from the pole pieces 1 and 2 by spacers 11 and 12 of non-magnetic and non-conducting material, such as wood. The parts are so proportioned that with bar B in place, the reluctance of the magnetic circuit for core A is substantially the same as the reluctance of this circuit when the core is located over an open-circuited trackway inductor. The bar B is provided with a winding 15 arranged to be connected in a circuit with a source of current such as a battery 14 and a variable resistance 17, or in circuit with a dissipating resistance 20. An ammeter 18 is permanently connected to winding 15. A quick acting switch S having a lever 16 and contacts 19 and 21 is so arranged that contacts 16-21 and 16-19 are both closed during part of the movement of the switch from either extreme position to the other. This arrangement prevents winding 15 from being open circuited when the switch is being thrown from contact 21 to contact 19 for a purpose which will appear hereinafter.

When switch S is closed at contact 21, current from battery 14 flows through winding 15 of bar B, and creates in this bar a magnetic flux which opposes the flux resulting from the current in winding 3. By variations in the value of resistance 17, the current in winding 15 is adjusted until the resulting flux through the core A is reduced to a value corresponding to the flux traversing this core when the core is not over a trackway inductor. If now switch S is thrown to make contact at 19, the flux due to the current in winding 15 will die away, and will induce a current in the circuit comprising the winding 15, ammeter 18, and dissipating resistance 20, contacts 19 and 21 being bridged by lever 16 for an instant in throwing the switch from contact 21 to contact 19 to prevent the winding 15 from being open-circuited and offering an infinite resistance to the current flow. If the combined resistance of battery 14 and resistance 17 is low compared with resistance 20, prac-

tically no change in current through the winding 15 occurs when contacts 21 and 19 are bridged. The induced current will be dissipated in resistance 20 and the time required for the current to drop substantially to zero will depend upon the time constant of the circuit including winding 15 and dissipating resistance 20.

I have found that by properly proportioning the inductance and resistance in the dissipating circuit, the collapse of the magnetic field due to current in winding 15 may be made to very closely simulate the actual condition which occurs when a receiver passes over an open circuited trackway inductor at a specified speed. The time constant of the dissipating circuit may be expressed as

$$\frac{L}{R_{15} + R_{20}}$$

where L represents the inductance of the testing device when clamped to the receiver A with normal current flowing in the receiver coils; R_{15} represents the resistance of winding 15, and R_{20} represents the resistance of dissipating resistance 20. By simply varying the resistance 20, any desired speed may be simulated and resistance 20 may be calibrated directly in miles per hour. For example, I have found that when the resistance $(R_{15} + R_{20})$ in ohms has approximately five and one-half times the value of the inductance L in henries, the decay of current through the dissipating circuit corresponds to the movement of a receiver over an open-circuited track inductor at a speed of one and one-half miles per hour. R_{15} should be taken as the effective resistance of 15 corresponding to the rate of change of flux used. The collapse of the field due to the current in the winding 15 causes the flux from winding 3 which links winding 4 to increase and the effect of this increased flux is to induce an electromotive force in winding 4 in exactly the same manner as though the actual reluctance of the magnetic circuit through core A had been decreased by the passage of the receiver over a trackway inductor at a specified speed.

Prior to using the apparatus for actual testing it is determined, by experiment or by calculation, what value of current is necessary in winding 15 to create a flux of such magnitude that the resulting flux conditions in the core A are substantially the same as those which exist when the core is not over a trackway inductor.

In actual testing, then, bar B is clamped in place as shown in Fig. 1, and switch S is closed at contact 21. Resistance 17 is then adjusted until ammeter 18 indicates that the predetermined proper value of current is flowing in winding 15, and resistance 20 is adjusted to the speed at which it is desired that the train carried apparatus shall

operate. Switch S is then thrown to contact with 19. The resulting collapse of the magnetic field created by the current in winding 15 will cause an electromotive force to be induced in winding 4 as explained hereinbefore. If the train carried apparatus is properly adjusted this electromotive force will cause relay R to open, and the opening of front contact 8 of this relay will de-energize magnet valve V and cause an automatic application of the brakes. If, with resistances adjusted as just described, the throwing of switch S does not cause the de-energization of relay R, the train carried apparatus is adjusted by means of resistances 10 and 7 until the operation of switch S causes relay R to become de-energized.

The train carried apparatus is then reset, switch S is again operated, and resistance 20 is adjusted so that the current through winding 15 will die out more slowly than for the test just described. Switch S is then operated again. The parts of the train carried apparatus should be so adjusted that under these conditions the closing of contact 19 will not de-energize relay R. The resistances 10 and 7 are so adjusted that the train carried apparatus will operate properly for the two values of resistance 20. That is, to say, the adjustment should be such that for a value of resistance 20 which simulates one rate of passage of the core over a trackway inductor, the train carried apparatus will be actuated when switch S is thrown to contact 19 but that for a smaller value of resistance 20 corresponding to a slower speed the train carried apparatus will not be actuated when this switch is operated. Assurance is thereby given that the train carried apparatus will not be actuated by a trackway inductor having the circuit for its nullifying winding closed. By adjustment of resistance 20 the train carried apparatus may be set to operate at any desired speed. By increasing or decreasing the thickness of spacers 11 and 12 the effect of high or low track inductors at various speeds may be obtained.

Although I have herein shown and described only one form of testing device embodying my invention and only one method of using such form it is understood that various changes and modifications may be made therein within the scope of the appended claims without departing from the spirit and scope of my invention.

Having thus described my invention, what I claim is:

1. The combination with a train carried receiver including a magnetizable core and spaced pole pieces, of a magnetizable bar having a winding thereon, a source of current for energizing said winding, a dissipating resistance calibrated to simulate different train speeds, and means for connecting

the winding to the dissipating resistance after said winding has been energized from said source.

2. The combination with a train carried receiver including a magnetizable core and spaced pole pieces, of a magnetizable bar having a winding thereon, a source of current for energizing said winding, a dissipating resistance calibrated to simulate different train speeds, and connected to one end of said winding, and means for connecting said winding and said resistance in series without open circuiting the winding.

3. The combination with a train carried receiver including a magnetizable core and spaced pole pieces, of a magnetizable bar having a winding thereon, two switch contacts, a source of current and a variable resistance connected to one of said contacts and to one end of said winding, a dissipating resistance connected to the other contact and to the same end of said winding, and a switch connected to the other end of said winding and arranged to momentarily bridge the two contacts when a connection between the winding and the dissipating resistance is made.

4. The method of testing railway traffic controlling apparatus comprising a magnetizable core, means for creating a first magnetic flux in said core, and governing means responsive to variations in said flux, which consists in creating a second flux in said core and allowing it to dissipate by sending current through a resistance calibrated to simulate different train speeds.

5. The method of testing railway traffic controlling apparatus comprising a magnetizable core, means for creating a first magnetic flux in said core, and governing means responsive to variations in said flux, which consists in clamping a magnetizable bar across said pole pieces, creating a magnetic flux in said bar and allowing it to dissipate by sending current through a resistance calibrated to simulate different train speeds.

6. The method of testing railway traffic controlling apparatus comprising a magnetizable core having spaced pole pieces, means for creating a magnetic flux in said core, and governing means responsive to variations of a predetermined magnitude in said flux, which consists in clamping a magnetizable bar across said pole pieces, creating in said bar a flux of known magnitude which opposes the flux in the core, and allowing it to dissipate by sending current through a circuit having a rate of current decay equivalent to the train speed for which the governing means is adjusted.

7. The method of testing railway traffic controlling apparatus comprising a train carried magnetizable core having spaced pole pieces, means for creating a first mag-

netic flux in said core and governing means responsive to a change in the value of said first flux from its normal value to a higher value, which consists in locating a magnetizable bar across said pole pieces so that the flux in said core attains said higher value, creating in said bar a second flux in opposition to said first flux so that the re-

sultant flux in said core is at its normal value and then allowing the second flux to 10 dissipate by sending current through a resistance calibrated to simulate different train speeds.

In testimony whereof I affix my signature.

PAUL N. BOSSART.
